UNITED STATES PATENT OFFICE.

JOHN T. FOSTER, OF ARLINGTON, NEW JERSEY.

TOWEL-RACK AND CLOTHES-BAR.

SPECIFICATION forming part of Letters Patent No. 292,294, dated January 22, 1884.

Application filed March 17, 1883. (No model.)

To all whom it may concern:

Be it known that I, JOHN T. FOSTER, of Arlington, Hudson county, New Jersey, have invented certain new and useful Improvements 5 in Towel-Racks and Clothes-Bars, of which the following is a specification.

My invention relates to that class of towel-racks or clothes-bars designed to be hung upon or fastened to the wall, and which consist 10 of a base-bracket or wall-plate on which a series of radial wooden arms or bars are pivoted on a common pin, one above the other, so that the bar may be swung out or diverged in a fan-like form to receive the towels or other articles to be dried; or, on the other hand, the 15 bars may all be swung or folded back flatwise against the wall when not required for use.

My invention aims to provide a rack of this class which may be made on a larger scale for 20 a heavier and more extensive range of work than those heretofore made—such as clothes-horses for laundry uses, &c.—and which shall possess greater strength and capacity with 25 ease of management and portability; and the invention consists in the peculiar construction and arrangement of parts hereinafter more fully described, and then pointed out in the claims.

In the drawings annexed, Figure 1 presents 30 a plan view of my improved rack with the arms diverged or outspread. Fig. 2 is a front elevation with the arms all folded flatwise against the base-plate, the outer ends of the arms being represented as broken off. Fig. 35 3 is a side elevation of Fig. 2 with the arms cut off and shown in cross-section. Fig. 4 is a fragmentary sectional plan or cross-section through the base-plate and the pivot-pin of the arms. Fig. 5 is a rear elevation or back 40 view of Fig. 2. Fig. 6 is a front view of the wall plate or cleat on which the base-plate or bracket may be socketed, and thereby supported on the wall.

In the drawings, *a* indicates the wall-bracket or base-plate of the device, which, as usual, is preferably made of cast-iron, with a flat back, adapted to rest directly against the face of the wall or other supporting surface.

d d indicate the radial bars or arms of the 50 rack, which are strung or pivoted on a long axial pin, *c*, which passes successively through the inner ends of each of the bars, and is sup-

ported at each end in lugs *b b*, which project at right angles from the front of the base-plate at top and bottom thereof, in about the usual manner, as shown. The arms *d* are thus pivoted on said pin *c* in close superposed order, one above the other between the lugs, and are capable, as usual, of being turned on said pin, so as to be swung or outspread in the diverging or fan form, as shown in Fig. 1, whereby each arm is adapted to support some article of clothing or other object hung thereon; and when the use of the rack is not required all the arms may be folded back 65 against the base-plate, as shown in Figs. 2, 3, and 5.

In Fig. 1 the rack is shown extended, and *g g* indicate links connecting one arm with the next. These links are preferably made 70 in the form of little flat metal plates stamped from sheet metal of any suitable kind. The broad and flat face of each plate rests on the top of each arm, and one end of the plate is bent downwardly and fastened to the back 75 side of the bar by a small screw or other fastening, as seen best at *g'*, in Fig. 5, also in Figs. 1 and 3, while the opposite end of the plate is bent upwardly, as shown at *g''*, in Figs. 2, 3, 1, and 4, and projects up in front of the 80 next overlying bar, as will be readily understood from the drawings. A small, tongue, *h*, is cut out of the top or broad face of the plate, and is bent upward opposite to the back bend, *g'*, as seen best in Figs. 1, 3, and 5, 85 so as to form a stop against which the back side of each bar will strike when folded back, as seen in Figs. 3 and 5. It will therefore be seen that, when all the bars are folded back, as shown in Figs. 2, 3, and 5, the back of 90 each overlying bar will be in contact with the tongue *h* on the bar next below it, and that the upper bend or front claw, *g''*, on each of the plates *g g* will project up in front of the bar next above it; hence by seizing the top 95 bar and swinging it around, it will contact with the front claw on the plate of the underlying bar and thus swing that bar with it, which in turn will contact with the claw of the next lower bar, and so on in successive order, so that when the first bar is moved around to its limit, as shown in Fig. 1, all the arms will be properly diverged, as will be readily appreciated. The first bar is provided with a

catch or hook, *i*, which may be hooked over a pin, *k*, projecting from the top of the base-plate, or, rather, from the top of the stepped rim *f*, which will then hold or lock the several arms firmly in their diverged position, as fully shown in Fig. 1. It will be seen that each link forms a shoe on which its bar rests on the rim *f*, and thus the bars are prevented from wearing by contact with the metallic steps of the rim, which usually causes the bars to sag and droop downward. The plates thus perform a double function.

If desired, the hook *i* may be pivoted on the top of the base-plate and the pin *k* may project from the top bar, *d*, or any other equivalent form of catch may be used, if preferred.

By reference to Figs. 2 and 5, it will be noted that the base-plate *a* is formed with a perforated ear, *a'*, at top and bottom, whereby the base-plate may be screwed permanently to the wall, so as to affix the rack in a permanent position thereon, if desired. I greatly prefer, however, to have the rack capable of a readily removable attachment to the wall, so that it can be hung thereon when in use and easily removed when not required, and may also be changed from place to place about the walls of the kitchen or laundry, according to circumstances or for the best position for drying. For this reason I construct the base-plate *a* with a large central socket opening or slot, *m*, of tapering or wedging form, as shown well in Figs. 2 and 5, with its vertical edges dovetailed, as shown in the sectional view, Fig. 4, and adapted to fit upon or engage with a similarly-formed wedging-plate, *n*, (see Fig. 6,) having its edges dovetailed at a reverse inclination to match the edges of the slot *m*, as seen in Fig. 4. The plate *n* is formed with two screw-holes, as seen in Fig. 6, whereby it may be screwed firmly against the wall or other support with its narrow end upward, as will be understood. The slot *m* in the base-plate corresponds in form with the wedging-plate *n*, as before described, but is longer than the plate at the wide end, so that the wide end may be easily slipped over the wedging-plate, and when the base-plate is then pressed down on the wedging-plate the two will become

firmly engaged by a wedging dovetailed action, as will be readily understood by reference to Figs. 1, 4, 5, and 6, thus enabling the rack to be firmly sustained upon the wall in a manner which admits of its easy removal when required. A number of the wedging-plates *n* may be furnished with one of the racks, so that the plate may be fixed in different positions on the mantel or wall about or above the fireplace or stove, or on the walls in convenient or favorable positions for drying, so that the rack may be changed from place to place, as required, or several may be put in use at the same time, and when not required may be easily taken down and put away, thus presenting an important advantage in the way of 65 portability and compactness.

The sides or edges of the slot *m* and plate *n* need not be tapering or wedging, as shown, but may be straight but with dovetailed edges to engage in the manner described; but I prefer for the wedging form.

I am aware of the Patents Nos. 54,727 and 92,794, and make no claim to the construction shown therein.

What I claim is—

1. The combination, with a base-plate, *a*, of the bars *d*, pivoted thereon, the semicircular stepped rim *f*, and the chain of links *g* *g*, constructed and applied to the bars *d* substantially as described, whereby they perform the 80 double function of moving the bars and protecting them from wear, as and for the purpose set forth.

2. In a towel-rack, substantially as shown, and in combination with the base-plate *a*, the pivot-pin *c*, step part *f*, and overlying bars *d*, the series of links *g*, secured to the bars *d* and having the projections *g'*, *h*, and *g'*, the said links being attached to the bars, as described, so as to intervene between the bars and the 90 steps, the hook *i*, and stud *k*, all arranged and adapted to serve as and for the purposes set forth.

JOHN T. FOSTER.
